UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET CUTTING AND FOLDING MACHINE.

1,193,450.

Specification of Letters Patent.

Patented Aug. 1, 1916.

Application filed June 4, 1915. Serial No. 32,172.

To all whom it may concern:

Be it known that I, HOWARD M. BARBER, a citizen of the United States, and resident of Stonington, in the county of New London 5 and State of Connecticut, have invented a new and useful Improvement in Sheet Cutting and Folding Machines, of which the following is a specification.

The object of this invention is to provide 10 means whereby the speed of continuously moving groups of sheets may be abruptly retarded and the groups of sheets folded off at a surface speed less than the speed of travel of the web as it passes through the 15 press and into the cutting and folding machine.

In sheet cutting and folding machines as heretofore produced where the folding mechanism operated at the speed of the 20 press, the output of the press was materially limited by the inability of the folding mechanism to act successfully at as high a speed as the press was capable of operating, the speed of the press being thereby necessarily 25 tied down to the highest efficient speed of the folding mechanism. By my invention, a folding mechanism operating at a lesser speed than that of the press can be used in conjunction with the press without additional strain on the folding mechanism 30 thereby permitting the running of the press at a much higher rate of speed than heretofore possible.

A practical embodiment of my invention 35 is represented in the accompanying drawings, in which—

Figure 1 is a section adjacent to the near side frame of so much of a cutting and folding machine as embodies my invention, Fig. 40 2 is a diagrammatic section taken from front to rear intermediate the side frames, Fig. 3 is a section taken adjacent to the far side frame, and Fig. 4 is a detail view showing the driving connection between several 45 parts.

The web, as it passes from the press, not shown herein, is led between the rollers 1, 2, and from thence downwardly between the pair of coacting rotary cutters 3, 4, mounted 50 on the shafts 5, 6. Guides 7, 8, direct the web to the collecting cylinder 9 mounted on the shaft 10, which collecting cylinder is herein shown as provided with three sets

of grippers 11, 12, 13. A curved guide 14 is provided at the under side of the collecting cylinder 9. The first transfer cylinder 15 is mounted on a shaft 16 and is provided with a single set of grippers 17. This cylinder is also provided with sheet spring pushers 18, 19, 20, for guiding the leading 60 edges of the sheets into the grippers 11, 12, 13, of the collecting cylinder 9. A curved guide 21 is provided around the under side of the first transfer cylinder 15. The second transfer cylinder 22 is mounted on a 65 shaft 23 and is provided with a single set of grippers 24. The male folding cylinder 25 is mounted on the shaft 26 and is provided with two sets of grippers 27, 28, and two folding blades 29, 30. A curved guide 31 is arranged around a portion of the under side of the male folding cylinder 25. The female folding cylinder 32 is mounted on a shaft 33 and is provided with two sets of folding jaws 34, 35, arranged to coact 75 with the folding blades 29, 30. A curved guide 36 extends partway around one side of the female folding cylinder 32. The delivery cylinder 37 is mounted on a shaft 38 and is provided with two sets of grippers 80 39, 40, arranged to take the folded groups of sheets from the folding jaws 34, 35, respectively, and deliver them into a suitable delivery device, such, for instance, as a pocketed delivery 41. A guide 42 extends 85 part way around one side of the delivery cylinder 37. If so desired, one or more slitters 43 may be provided arranged to coact with the delivery cylinder 37 for slitting the sheets lengthwise of their travel into a plurality of sections before they are delivered to the delivery device 41.

The several mechanisms are driven from the press, not shown, through the gear 44, as follows: The cylinders 22, 25, 32 and 37 95 are driven at a surface speed about one-half the speed of the web through the gears 45, 46, 47, 48. The collecting cylinder 9 and first transfer cylinder 15 are driven at a surface speed twice that of the cylinders 100 22, 25, 32, and 39, through the gears 49, 50, 51, 52, and the rotary cutters are driven through the gears 53, 54. The web feed rolls 1 and 2 are driven through the gears 55, 56, 57. It will thus be seen that the rotary cutters are driven two revolutions for 105

each revolution of the first transfer cylinder 15 and the collecting cylinder is driven one and one-third revolutions for each revolution of the transfer cylinder 15. It will also be seen that the second transfer cylinder travels one revolution for each revolution of the first transfer cylinder 15 and therefore travels at one-half the surface speed of the said transfer cylinder 15 but at the same surface speed as the folding and delivery cylinders. The sheet spring pushers 18 are mounted on a rock shaft 58 so that the pushers may be drawn in under the surface of the cylinder 15 when the sheets are transferred to the slow moving cylinder 22. This is necessary to prevent the pushers 18 from marking the sheet next to the cylinder 15 after the group of sheets has been transferred to the cylinder 22. The spring pushers 19 and 20 may be fastened in fixed positions to the surface of the cylinder 15 and stand out a sufficient distance beyond its periphery to force the leading edges of the sheets over against the surface of the collecting cylinder 9 and into the respective grippers thereon. It is to be understood that these pushers 19 and 20 never pass or drag over the printed portions of any of the sheets and it is therefore unnecessary to mount them on rock shafts. A fixed cam 59 is arranged in position to successively open the grippers on the collecting cylinder 9 for receiving the sheets. A movable cam 60 controlled by a box cam 61, is arranged to successively open the grippers of the collecting cylinder every one and one-third revolution of the collecting cylinder for transferring the sheets to the first transfer cylinder 15. Fixed cams 62, 63, are arranged in position to operate the grippers 17 for receiving the sheets from the collecting cylinder and transferring the sheets to the second transfer cylinder. A fixed cam 64 is arranged in position to operate the grippers 24 of the second transfer cylinder 22 for transferring the group of sheets from the cylinder 15 to the folding cylinder 25. Fixed cams 65, 66, are arranged in position to operate the grippers 27, 28, to receive the sheets from the second transfer cylinder and to release the sheets at the time of the folding operation. Fixed cams 67, 68, 69, of well known and approved form are provided for floating and opening the folding jaws 34, 35, to receive the sheets from the folding cylinder 25 and transfer them to the delivery cylinder 37. Fixed cams 70, 71, are provided for operating the grippers 39 of the delivery cylinder for receiving the folded sheets from the folding cylinder 25 and delivering the same to the delivery device 41.

In operation: The web as it comes from the press passes downwardly between the cutters 3, 4, where it is cut transversely

into sheets. The collecting cylinder 9 collects three sheets and transfers them together with the fourth sheet every one and one-third revolutions of the collecting cylinder 9 to the grippers 17 of the first transfer cylinder 15. The group of sheets is then transferred from the grippers 17 on the cylinder 15 to the grippers 24 on the cylinder 22 which transference will cause the abrupt retardation of the sheets. As the sheets are at the under side of the cylinder 15 when they are transferred to the cylinder 22, the sheets will fall away from the surface of the cylinder onto the guide 21 and will not be disturbed by the more rapidly moving cylinder 15 after the control of the group of sheets has been assumed by the cylinder 22. The grippers 24 will, in turn, transfer the sheets to either the grippers 27 or 28 of the folding cylinder 25 at the surface speed of the said folding cylinder. The group of sheets will then be folded off to the cylinder 32 and transferred therefrom to the delivery cylinder 37 where the folded group of sheets may be slit lengthwise of its travel into a plurality of sections and then delivered to the delivery device 41.

By the term "cylinder" as used in the description, I contemplate any suitable means for passing the sheets and signatures through the prescribed path and by the term "grippers" I wish to include any engaging devices suitable for the purpose of leading the sheets or signatures through said prescribed path.

It is evident that various changes may be resorted to in the construction, form and arrangement of the various parts without departing from the spirit and scope of my invention; and hence I do not wish to limit myself strictly to the form herein shown and described, but

What I claim is:—

1. In a machine of the character described, means for cutting sheets from a traveling web, sheet folding mechanism traveling at a lesser speed than the web and means for feeding the sheets to the folding mechanism at the speed thereof.

2. In a machine of the character described, means for cutting sheets from a traveling web, sheet folding mechanism traveling at a lesser speed than the web and means for retarding the sheets and feeding them to the folding mechanism at the speed thereof.

3. In a machine of the character described, means for cutting sheets from a traveling web, sheet folding mechanism traveling at a lesser speed than the web and means for abruptly retarding the sheets and feeding them to the folding mechanism, at the speed thereof.

4. In a machine of the character de-

- scribed, means for cutting sheets from a traveling web, sheet folding mechanism traveling at about half the speed of the web and means for feeding the sheets to the folding mechanism at the speed thereof. 5
5. In a machine of the character described, means for cutting sheets from a traveling web, sheet folding mechanism traveling at about half the speed of the web 10 and means for retarding the sheets and feeding them to the folding mechanism at the speed thereof.
6. In a machine of the character described, means for cutting sheets from a traveling web, sheet folding mechanism traveling at about half the speed of the web 15 and means for abruptly retarding the sheets and feeding them to the folding mechanism at the speed thereof.
- 20 7. In a machine of the character described, a sheet carrying mechanism traveling at a certain speed, a sheet folding mechanism traveling at a lesser speed and an interposed sheet transfer mechanism 25 traveling at the speed of the folding mechanism.
8. In a machine of the character described, a sheet collecting mechanism traveling at a certain speed, a sheet folding mechanism traveling at a lesser speed and an interposed sheet transfer mechanism 30 traveling at the speed of the folding mechanism.
9. In a machine of the character described, a sheet carrying mechanism traveling at a certain speed, a sheet folding mechanism traveling at a lesser speed and a sheet transfer mechanism arranged to retard the sheets as they pass from the carrying 35 mechanism to the folding mechanism. 40
- 45 10. In a machine of the character described, a sheet carrying mechanism traveling at a certain speed, a sheet folding mechanism traveling at a lesser speed and a sheet transfer mechanism arranged to abruptly retard the sheets as they pass from the carrying mechanism to the folding mechanism.
11. In a machine of the character described, a sheet collecting mechanism traveling at a certain speed, a sheet folding mechanism traveling at a lesser speed and a sheet transfer mechanism arranged to retard the sheets as they pass from the collecting 50 mechanism to the folding mechanism. 55
12. In a machine of the character described, a sheet collecting mechanism traveling at a certain speed, a sheet folding mechanism traveling at a lesser speed and a sheet transfer mechanism arranged to abruptly re-
- tard the sheets as they pass from the collecting mechanism to the folding mechanism. 60
13. In a machine of the character described, a sheet carrying cylinder traveling at a certain surface speed, a sheet folding cylinder traveling at a lesser surface speed 65 and an interposed sheet transfer cylinder traveling at the speed of the sheet folding cylinder and operable to take the sheets from the sheet carrying cylinder and transfer the sheets to the folding cylinder. 70
14. In a machine of the character described, a sheet collecting cylinder traveling at a certain surface speed, a first sheet transfer cylinder traveling at the same surface speed, a sheet folding cylinder traveling at 75 a lesser surface speed and a second sheet transfer cylinder traveling at the surface speed of the folding cylinder and operable to take the sheets from the first transfer cylinder and to transfer the sheets to the 80 folding cylinder.
15. In a machine of the character described, means for cutting sheets from a traveling web, mechanism for collecting sheets cut therefrom, sheet folding mechanism traveling at a lesser speed and sheet transfer mechanism arranged to abruptly retard the sheets as they pass from the collecting mechanism to the folding mechanism. 85 90
16. In a machine of the character described, means for cutting sheets from a traveling web, a sheet carrying cylinder traveling at a certain surface speed, a sheet folding cylinder traveling at about one-half 95 the surface speed of the sheet carrying cylinder and a sheet transfer cylinder traveling at the surface speed of the folding cylinder for transferring the sheets from the carrying cylinder to the folding cylinder. 100
17. In a machine of the character described, means for cutting sheets from a traveling web, a sheet collecting cylinder traveling at a certain surface speed, a first sheet transfer cylinder traveling at the same 105 surface speed, a sheet folding cylinder traveling at about one-half the surface speed of the collecting and first transfer cylinders, and a second sheet transfer cylinder traveling at the surface speed of the folding cylinder and arranged to transfer the sheets 110 from the first transfer cylinder to the said folding cylinder.
- In testimony, that I claim the foregoing as my invention, I have signed my name, 115 this second day of June A. D. 1915.

HOWARD M. BARBER.
